MEDICAL ELECTRODE

Elmer A. Piar, Cleveland, Ohio

Application May 12, 1948, Serial No. 26,599

3 Claims. (Cl. 128—303.14)

1

This invention relates to electro-surgical apparatus and particularly to apparatus for the mechano-electrolytical stimulation of hair growth on the human scalp.

The primary object of this invention is to provide an improved medical electrode for use with non-pulsating low voltage, high amperage galvanic current that will dissect the non-cellular tissues that cover the skin without causing a flow of blood.

Another object is to provide a device of the type stated that will remove such non-cellular tissue so that the sudoriferous and subaceous glands may again function normally and allow the hair follicles to reproduce hair.

These and other objects of the invention will become apparent from a reading of the following specification and claims together with the accompanying drawings wherein like parts are referred to and indicated by like reference characters and wherein:

Figure 1 is a perspective view of the assembled apparatus showing the control cabinet and the electrodes associated therewith;

Figure 2 is a front view of the handle of the medical electrode;

Figure 3 is a longitudinal sectional view taken along the line and in the direction of the arrows 3—3 of the Figure 2;

Figure 4 is an end view of the handle taken in the direction of the arrows 4—4 of the Figure 2;

Figure 5 is a bottom view of an electrode operating head of the unitary type having fixed cutting edges;

Figure 6 is a top view of the same;

Figure 7 is an end view of the same;

Figure 8 is a front view of an assembled medical electrode of the type having replaceable cutting blades;

Figure 9 is a right end view of the assembled electrode shown in the Figure 8 with the handle broken away;

Figure 10 is a plan view of the unassembled body member;

Figure 11 is a front view of one of the guide members;

Figure 12 is an end view of the unassembled body members; and

Figure 13 is a front view of one of the electrode cutting blades.

Referring to Figure 1 there is seen a device made in accordance with this invention. Reference character 20 indicates a cabinet which houses two sources of direct current and the controls therefor. One source being a set of dry

2

batteries 25 rated at 4½ volts, and the other being a conventional electronic-tube full-wave rectifier 31. The rectifier permits the use of 110 volt 60 cycle alternating current to operate the device. The alternating current is converted and reduced to direct current at 4½ volts pressure. Three dry cells compose the 4½ volt battery 25. The battery 25 has its positive pole connected to the binding post 22 and its negative pole connected to the first terminal of the switch 24. The second terminal of the switch 24 is connected to one of the end terminals of the potentiometer 26. The center terminal of the potentiometer is in turn connected to one terminal of the milliammeter 30. This meter should have a 0 to 5 milliampere range. The second terminal of the meter 30 is connected to the first coil-terminal of a D'Arsonval type relay 27. The second coil-terminal of the relay is connected to the negative binding post 23. The relay 27 has its switch mechanism connected to the pilot light 28 and the pilot light battery 29, which is a single 1½ volt dry cell. Dotted lines are used to indicate the wired connections. The rectifier 31 is plugged into a source of alternating current by means of the plug 33. The positive side of the rectified current is connected to the second end terminal of the potentiometer 26 which is in turn connected to the positive binding post 22. The negative side of the rectified current is connected to the switch 32 which is in turn connected to the first end terminal of the potentiometer 26 as is shown in the Figure 1.

The medical electrode 40 is connected to the negative binding post 23 by means of a flexible cable 35 while an indifferent electrode 34 adapted to contact with the body of the patient constituting the subject to be operated on, is connected to the positive binding post 22 by means of a second flexible cable 36.

Figures 2, 3 and 4 show the electrode handle 41 which has a threaded stud 43 adapted to engage the hereafter described operating head 80. A terminal hole 42 in the other end of the handle 41 serves as a jack to receive the terminal plug 37 of the flexible cord 35 as shown in the Figure 8. In its preferred form the handle is turned from a brass rod and has a knurled gripping surface. Since the voltages used are low the handle 41 need not be covered with insulating material.

The preferred form of head 80 is shown in the Figures 5, 6 and 7. The head is machined from a single rectangular block of tool steel which is cut to a semicircular cross section as shown in

the Figure 7. The head is approximately $1\frac{1}{2}$ inches long and has a plurality of arcuate cutting edges 82 shaped and ground to razor-like sharpness, on its arcuate surface. These edges must be closely spaced, and in the preferred form are spaced fifteen thousandths of an inch apart. An arcuate guide surface 81 approximately $\frac{1}{8}$ inch wide, is formed at either end of the head 80. This surface is ground one thousandth of an inch below the plane of the cutting edges 82. A threaded hole 83 on the flat upper surface of the head is adapted to receive the threaded stud 43 of the handle 41.

A modified form of head construction is shown in the Figures 8, 9, 10, 11, 12 and 13. In the modified form the head comprises a body member 50, guide members 60 and individual blade members 70.

The body member is made from a rectangular block of steel and has a longitudinal slot 54 in its lower side and a threaded handle hole 51 in its upper side. Reference character 52 indicates a round guide mounting hole and reference character 53 indicates an elongated guide mounting hole as shown in the Figures 10 and 12.

The guides 60 are approximately $\frac{1}{8}$ inch wide and have an arcuate bearing surface 61 and a key 62 shaped to fit the body slot 54. A vertical threaded mounting hole 63 is formed in the top of the key 62 while a centrally located horizontal hole 64 is drilled through the body of the guide 60. The cutting blades 70 are made from steel strip of the type used for making safety razor blades and are shaped as shown in the Figure 13 with a key 72, arcuate cutting edges 76 and a central hole 74. The edges 76 are ground to a razor-like fineness and all the blades 70 must match as to contour and size.

The curve to which each cutting edge 76 is ground must have the same center but a greater radius than the curve of the arcuate guide bearing surfaces 61. However, the radius of each arcuate edge 76 must not be more than one-half to one thousandth of an inch greater than the radius of the arcuate bearing surface of the guides 60. This difference determines the depth of cut taken by the instrument. If these limits are exceeded the efficiency of the instrument will be impaired.

The head is assembled by inserting the key 62 of one of the guides 60 into the body slot 54, and aligning the keyhole 63 with the round guide mounting hole 52. The first guide is then locked in place by means of a screw 55 that passes through the body hole 52 and engages the threaded hole 63 of the guide key 62. The required number of cutting blades necessary to fill up the remainder of the slot after making allowances for the second guide member are then assembled on the body member 50 with their keys 72 engaged with the body slot 54 as shown in the Figure 8. The cutting edges 76 should be spaced between ten and fifteen thousandths of an inch apart. Spacers 75, of appropriate thickness, are used to give the proper spacing between cutting edges. If the spacing is less than ten thousandths of an inch the removed tissue will clog up the cutter head interstices, while if the spacing is greater than fifteen thousandths of an inch the blades have a tendency to gouge the skin and cause irregular tissue removal. After the required number of blades and spacers are positioned on the body the second guide member is mounted in the body slot and a compression screw 65 is passed through the guide holes 63 and the

blade holes 74. The second guide is loosely mounted on the base by means of a second mounting screw 56 which passes through the elongated mounting hole 53 of the body 50.

The compression screw 65 is then tightened until the guides and blades form a solid compact unit after which the second mounting screw 56 is tightened which locks the cutting blades and guides to the body 50. With a head of this type dull blades can be replaced at will and the depth of cut can be varied by using guides of different radius. The handle 41 is mounted in the handle hole 51. The assembled medical electrode in its modified form is shown in the Figure 8.

The operation of the apparatus is as follows: The indifferent electrode 34 is held by the patient or otherwise attached to the patient's body. To operate on the $4\frac{1}{2}$ volt battery 25 the switch 24 is thrown to its "on" position. The medical electrode 40 is then brought into contact with the patient's scalp and the potentiometer is adjusted until the milliammeter reads between $\frac{1}{2}$ milliamperes and 2 milliamperes depending upon the condition of the patient's scalp. The relay 27 is set up to close the pilot light circuit when the current passing through its activating coil exceeds $\frac{1}{2}$ millampere, and to open the pilot light circuit whenever the current flow exceeds two milliamperes. Therefore as long as the current flow remains between the proper limits of $\frac{1}{2}$ to 2 milliamperes the pilot light 28 will glow and the meter 39 need not be constantly read. The medical electrode 40 is then gently passed over the scalp with the guides 60 resting on the skin. The blades 70 will then cut away a thin layer of the tough non-cellular tissue covering the scalp without causing the flow of blood. The depth of cut is determined by the relative positions of the blade edges 76 and the bearing surfaces 61 of the guides 60. In cases having a long history of baldness the cut should be one thousandth of an inch deep. In cases of recent baldness one-half thousandth of an inch is usually sufficient. It is believed that the passing of the galvanic current from the blade edges 76 to the skin tissue creates a condition wherein the tissue fluids are decomposed at the point of contact between edges 76 and the skin to form hydrogen peroxide which acts as a mild disinfectant to prevent infection of the scalp. The removal of the overlaying crustaceous layer of hard tissue leaves the scalp in condition favorable to the growth of new hair.

When it is desired to operate the apparatus 55 with alternating current the battery switch 24 is returned to its "off" position. The plug 33 is connected to a source of 110 volt, 60 cycle current and the switch 32 is moved to its "on" position. The controls and meter readings are then 60 adjusted in the same manner as when operating on the battery 25.

It will now be clear that there has been provided a device which accomplishes the objectives heretofore set forth. While the invention has been disclosed in a preferred and modified form; it is to be understood that the specific embodiments thereof as described and illustrated herein are not to be considered in a limiting sense as there may be other forms or modifications of the invention which should also be construed to come within the scope of the appended claims.

I claim:

1. A medical electrode, comprising in combination, a substantially rectangular metallic body member, having a longitudinally extending slot

in the lower face thereof, a pair of guide members mounted in the said slot at the ends thereof, each of the said guide members having an arcuate bearing surface, a plurality of spaced metallic operating blade members mounted in the said slot between the said guide members, each of the said blades having an arcuate edge that projects below the plane of the guide member bearing surfaces, and a conducting handle mounted on the upper surface of the body member, the said handle having terminal means thereon.

2. A medical electrode, comprising in combination, a substantially rectangular metallic body member having a longitudinally extending slot in the lower face thereof, a pair of guide members mounted in the said slot at the ends thereof, each of the said guide members having an arcuate bearing surface, a plurality of metallic operating blade members, having arcuate cutting edges, mounted in the said slot between the said guide members, each of the said cutting edges being spaced fifteen thousandths of an inch apart, the arcuate surfaces of the said guide members being one thousandth of an inch below the cutting edges of the said blade members, and a conducting handle mounted on the upper surface of the body member, the said handle having terminal means thereon.

3. A medical electrode, comprising in combina-

tion, a substantially rectangular metallic body member having a longitudinally extending slot in the lower face thereof, a pair of guide members mounted in the said slot at the ends thereof, 5 each of the said guide members having an arcuate bearing surface, a plurality of metallic operating blade members, having arcuate cutting edges, mounted in the said slot between the said guide members, each of the said cutting edges being spaced between ten thousandths and fifteen thousandths of an inch apart, the arcuate surfaces of the said guide members being between one-half a thousandth and one thousandth of an inch below the cutting edges of the said blade members, and a conducting handle mounted on the upper surface of the body member, the said handle having terminal means thereon.
